RONALD D. WHITE, OF LONDON, ONTARIO, CANADA, ASSIGNOR TO MOULDED PULP CORPORATION, OF CHICAGO, ILLINOIS, A CORPORATION OF ILLINOIS

SIDE PACKING BOARD FOR SHIPPING CASES

Application filed June 8, 1931. Serial No. 542,785.

This invention relates to improvements in packing boards employed for the protection during shipment and storage of fragile articles such as glass bottles; it more particularly relating to packing boards moulded from paper pulp designed to be placed between the articles and the sides of the shipping case.

In packing fragile articles, such as glass bottles, it is the practice to not only enclose the articles in packing material, but also insert between the articles thus enclosed and the sides of the shipping case other packing boards for the purpose of preventing the exposed ends of the articles from coming into direct contact with the shipping case, the well known form of corrugated board being usually employed for that purpose.

The object of the present invention is to provide the packing board to be employed as a side-pad of a nature which will not only separate the fragile articles from the sides of the shipping case but also act to support the same.

A further object of the invention is to provide a side-pad for packing board of this character which may be moulded from fibrous pulp to thereby cheapen the production of same and furnish a pad which will have a greater cushioning effect than that furnished by pads made from corrugated board.

In the accompanying drawing:

Fig. 1 is a perspective view of a packing case broken away to show the interior and show the relation of the improved side-pad with the packing boards.

Fig. 2 is a vertical section through the container such as illustrated in Fig. 1.

Fig. 3 is a top plan view of one of the improved side-pads.

An improved form of packing board is shown in the present case associated with packing enclosures for the articles of the type described in my pending application Serial No. 542,783, filed June 8th, 1931. These packing enclosures include mating complementary packing boards 1 and 2 which are formed with recesses or cavities conforming to the shapes of the articles to be packed, in the present case glass bottles. Each of these

cavities has a large portion 3 conforming to the body of the bottle and a reduced portion 4 conforming to the neck of the bottle with flat surfaces 5 at the outer end of each reduced neck-portion, and the alternate cavities extend in opposite directions and are in slightly staggered relation as described in said application. In the enclosures described in said application, the boards are made sufficiently wide so that the cavities will extend to or slightly beyond the bottoms of the bottles and it is the practice when using an enclosure of that character to place between the bottoms of the bottles and the sides of the packing case, pads of corrugated board to prevent the bottles from shifting in the cavities and making any contact with the sides of the packing cases. In the present case the packing enclosures 1 and 2 are made narrower so that the cavities will be of less length than the bottles, permitting the bottoms of the bottles to project a short ways there beyond.

The side-pad embodying my improvements is shown at 6 and is of a length and width substantially equal to the length and width of a side of the packing case indicated at 7. This side-pad is a flat sheet of moulded pulp provided with a plurality of cup-shaped recesses 8 of a size and so disposed as to receive the projecting ends of the bottles, these cup-shaped recesses being so positioned as to coincide with the cavities of the packing enclosures 1 and 2.

The shipping box for a given number of articles is no larger than previously used, it being observed that the sides thereof are merely spaced apart sufficiently to enclose the nested packing enclosures 1 and 2 and the side-pads 6.

By the arrangement the side-pads not only act to protect the articles from the sides of the shipping case but also act in conjunction with the packing enclosures to support the articles, assuming a part of the weight of the articles and thus provide an additional cushioning effect for the articles. Further, by moulding these side-pads from fibrous pulp, the expense of producing a side-pad is

materially decreased over the old form of corrugated side-pads.

Having thus described my invention I claim:

- 5 1. In combination with packing enclosures for fragile articles having a plurality of cavities extending alternately in opposite directions to receive and enclose the major portions of the articles but in which one end of each article projects beyond its corresponding cavity in connection with a shipping box, of a side-pad insertable between each side of the packing case and the articles and having means for engaging and supporting said projecting ends of the articles.
- 10 2. In combination with packing enclosures for fragile articles having a plurality of cavities extending alternately in opposite directions to receive and enclose the major portions of the articles but in which one end of each article projects beyond its corresponding cavity, in connection with a shipping box, of a side-pad insertable between each side of the packing case and the articles and having a plurality of recesses to receive such projecting ends of the articles.
- 15 3. The combination, with a shipping box, of packing enclosures for bottles having a plurality of cavities extending alternately in opposite directions to receive and enclose the major portions of the bottles, each cavity being of a length to permit a portion of the end of the body of the bottle to project therefrom, a side pad insertable between each side of the packing case and the packing enclosure and having a plurality of recesses to receive the projecting ends of the bottles, the recesses of one side pad being in staggered relation with the recess of the other side pad 20 when said pads are in position in the shipping case.
- 25
- 30
- 35
- 40

In testimony whereof, I have hereunto set my hand this 12th day of May, 1931.

RONALD D. WHITE.
